UNITED STATES PATENT OFFICE.

CHARLES H. COLES, OF CHICAGO, ILLINOIS.

DESIGN FOR A CALENDAR-BLOCK STAND.

SPECIFICATION forming part of Design No. 31,853, dated November 21, 1899.

Application filed September 23, 1898. Serial No. 731,495. Term of patent 7 years.

To all whom it may concern:

Be it known that I, CHARLES H. COLES, a citizen of the United States of America, residing at Chicago, in the county of Cook, in the State of Illinois, have invented and produced a certain new and original Design for Calendar-Block Stands, of which the following is a description.

Referring to the accompanying drawings, wherein like reference-letters indicate like or corresponding parts, Figure 1 is a perspective view of a calendar-block stand, showing my new design; and Fig. 2 is a transverse section of the same in line 2 2 of Fig. 1.

As shown in the drawings, the leading and material features of my design consist in a rectangular frame A, so formed that when placed upon a level surface the upper face

will be upwardly inclined and adapted to support a calendar-pad thereon. Upon the lower margin of the frame or stand a tray B is formed. The edge surfaces of the frame are provided with an ornamental scroll or figure C, as shown. As thus constructed the whole stand presents a neat and attractive appearance, admirably adapted for the purposes for which it is intended.

Having thus described my invention, what I claim as new, and desire to secure by Letters Patent, is—

The design for a calendar-block stand, as herein shown and described.

CHARLES H. COLES.
